CLAIM

The ornamental design for a instant coffee capsule, as shown and described.

DESCRIPTION

FIG. 1 is a perspective view of a capsule according to my design;

FIG. 2 is a top plan view thereof;

FIG. 3 is a side elevational view thereof, it being appreciated that the capsule as illustrated is symmetrical about a vertical centerline through the capsule;

FIG. 4 is a bottom plan view thereof; and,

FIG. 5 is an enlarged fragmentary cross-sectional view taken along line 5—5 of FIG. 4.
